UNITED STATES PATENT OFFICE.

DONALD S. BARROWS, OF ROCHESTER, NEW YORK, ASSIGNOR, BY MESNE ASSIGNMENTS, TO THE T. H. SYMINGTON COMPANY, OF NEW YORK, N. Y., A CORPORATION OF DELAWARE.

TRUCK SIDE FRAME.

Application filed April 30, 1920. Serial No. 377,826.

To all whom it may concern:

Be it known that I, DONALD S. BARROWS, a citizen of the United States, residing at Rochester, in the county of Monroe and State of New York, have invented certain new and useful Improvements in Truck Side Frames; and I do hereby declare the following to be a full, clear, and exact description of the invention, such as will enable others skilled in the art to which it appertains to make and use the same.

The invention relates to trucks for railway vehicles and more particularly to new and useful improvements in the construction of truck side frames.

The principal object of my invention, broadly stated, is to improve the construction of truck side frames of the arch bar type. To this end the main features of the invention consist in arranging the compression and tension members so that the points of intersection thereof lie closely adjacent to the vertical planes passed through the truck axles, and in interposing between the said members a new and improved form of combined strut, bolster guide and spring plank support.

Another feature of the invention resides in the form and arrangement of compression and tension members of the side frame.

Still another feature of the invention consists in interposing between each journal box and the adjacent ends of the compression and tension members a journal box seat adapted to cooperate with the said members and to afford a strong and simple connecting means between the same and to provide a simple and efficient means for connecting the journal boxes to the side frames.

Still another feature of the invention consists in providing a tension member composed of a plurality of flanged members or bars the opposite ends of which are connected to the compression member adjacent the ends thereof, the cross sectional area of the end portions of the said flanged members being at least equal to the cross sectional area thereof at a point intermediate the said end portions.

Still another feature of the invention consists in providing a strut member with removable wear plates and brake hanger brackets.

Another primary feature of the invention

resides in the construction of the journal box tie members.

To these and other ends the invention consists in certain improvements and combinations of parts as will be hereinafter more fully described, the novel features being pointed out in the claims at the end of the specification.

Referring now to the drawings wherein I have illustrated a single embodiment of the invention,—

Figure 1 is a perspective view showing the outer face of a complete side frame constructed in accordance with my invention.

Fig. 2 is a similar view illustrating the inner face of the side frame.

Fig. 3 is a view in front elevation on a slightly larger scale of a symmetrical portion of the side frame, portions of the frame being broken away to add to the clearness of the disclosure.

Fig. 4 is a horizontal sectional view taken on line 4—4 of Fig. 3.

Figs. 5 to 12, inclusive, are detail views, Fig. 5 illustrating the manner of connecting the brake hanger bracket to the strut column, the latter being shown in section.

Fig. 6 is a view in front elevation of a brake hanger bracket.

Fig. 7 is a transverse sectional view of the brake hanger bracket, and Fig. 8 is a sectional view on the line 8—8 of Fig. 7, the section being viewed in the direction indicated by the arrows adjacent the ends of the said line.

Figs. 9 and 10 are views in top plan and side elevation, respectively, of one of the journal box seats.

Figs. 11 and 12 illustrate a slight modification in the form and manner of connecting the bolster guide plates to the strut columns, Fig. 11 being a view in front elevation and Fig. 12 a view in vertical section, showing the guide plate in position.

Throughout the specification and drawings like parts are designated by like reference characters.

The numeral 1 designates generally the truck side frame which comprises a top arch or compression member 2, a strut member 3 which may be and preferably is formed of a hollow box member having a top member 4, upright columns 5, 5 and a bottom member 6, all of which will hereinafter be more

fully described. The lower arch or tension member preferably comprises a pair of flanged bars 8, 8, the said bars being adapted to extend under the strut member and to have their ends connected to the tension member 2 adjacent the end portions 9 thereof. The lower arch bars 8 may conveniently be formed from angle members having the flanges 9 disposed at right angles to each other. Intermediate the points of connection of the end portions of the bars 8 with the compression member 2 and the points of connection between the said bars 8 and the strut, one of the flanges 9 of each of the said bars 8 is warped or turned substantially on a helical curve so that the end portions 10 of each bar 8 lie in the plane of the upright flange 9 thereof.

Referring now to the form of strut member 3 illustrated in the drawings, it will be observed that for convenience the top member 4, the columns 5 and the bottom member 6 are all integrally connected preferably by casting the entire strut member as a unit. The bottom member 6 is conveniently made of greater width than the width of the column members 5, and is provided with a pair of downwardly extending flanges 11. The latter are, for convenience, spaced inwardly from the outer edges of the upper spring plank seat 12 of the member 6, and if desired a plurality of strengthening ribs, such as 13, may be provided to connect the said flanges to the outwardly extending portions of the seat 12. The end portions of the member 6 which also form the base of the respective columns 5, 5 are upwardly inclined as indicated at 14. The column members have been, for convenience, illustrated as formed from H-shaped portions 15, the laterally extending flanges 16 thereof being connected at spaced points by webs 17. The inner transversely extending web 16 of each column member is preferably thickened as shown at 18 adjacent the upper portion thereof, and may be provided with a plurality of openings 19 through which the bolts 20, or other equivalent fastening means which serve to connect the bolster guide plates 21, may extend.

In Figs. 11 and 12 I have illustrated a slight modification of this form of construction. In this form the column webs 16^a are provided with countersunk seats 22 each of which is adapted to receive the guide plate 21^a, the latter being furnished with a countersunk seat 23 and a plurality of openings 24 which, when the plates are in position, align with openings 19^a in the web 16^a, and in place of the bolts 20 I provide a U-shaped clip 25 the arms of which extend through the openings 24 and 19^a and are adapted to be bent as shown at 26 over the rounded projections 27 to maintain the guide plates in position. It will be understood of

course that this form of guide plate may be substituted for the form shown in Figs. 1, 2 and 3 of the drawings, if desired.

Adjacent the upper ends of each column 5 there is provided a frusto-conical seat 28, clearly shown in Fig. 5. Each of these seats opens on the inner face of the column and each is adapted to receive one of the brake hanger brackets 29 which are also provided with frusto-conical bearing portions 30 which cooperate with the correspondingly formed walls of the seats 28. The web 31, which substantially closes the inner end of the recess 28, is preferably provided with a key hole slot 32 and each brake hanger bracket may be furnished with a pair of lugs 33 which, when the brackets are in position, engage the side edges of the slot 32 and hold the bracket from rotation in the seat 28. Each bracket is preferably maintained in position by means of a bolt 35 and nut 34, and if desired a washer 36 and a lock washer 37 may be interposed between the nut and the outer face of the web 31. The brake hanger brackets are so formed as to have a taper fit within the recess 28, and are preferably driven into these recesses. It will be noted, however, that in case the brake hanger bracket 29 should be broken in service it may be readily detached and a new bracket substituted therefor without detriment to the truck side frame.

The upper member 4 of the strut is preferably designed so as to have a taper fit between the side flanges 38 of the top arch 100 or compression bar 2, this member being conveniently formed as a channel bar.

At the opposite ends of the compression bar 2 are provided journal box seats 39 each of which may be conveniently formed as a casting having a base member 40, upwardly extending flanges 41 which also have a taper fit between the flanges 38 of the bar 2 and which are offset inwardly as at 42, so that the lower portions 43 of said flanges will lie coincident with the outer faces of the flanges 38 of the channel bar compression member. The base 40 may be provided with strengthening ribs 44 and with raised bosses 45 which surround the bolt openings 46 through which the journal box bolts 47 extend. It will be observed that an opening 48 is provided in the web of the compression member 2 adjacent the ends thereof, the purpose and object of the said openings being to permit the insertion therethrough of the inner journal box bolt 47.

The lower portion of each journal box is connected to the strut member preferably by means of the journal box tie members 49 which are clearly shown in Fig. 4. The said tie members are conveniently formed from a sheared bar 50, the bar being sheared and bent substantially in the form of an

angle bar except that the flanges thereof are tapered in opposite directions, the upright flanges being deepest at points adjacent the strut while the transversely disposed flanges have their greatest width at portions adjacent the journal box. The said plates 50 are arranged so that one plate will overlie the other at their outer ends, and the journal box bolts 47 preferably extend through alined openings which are provided in both of the said bars. The inner ends of the said bars are connected to the flanges 11 of the strut 3 and the rivets 51 which serve to connect the same also form additional securing means for connecting the tension bars to the said strut. The transversely disposed flanges of both pairs of journal box tie plates are cut away as at 52 so as to permit the rivets 53 to be driven, the said rivets 53 passing through the portions 14 of the lower member 6 of the strut and through the transversely disposed flanges 9 of the tension bars 8.

It will be noted that the tension bars 8 are riveted to the journal box seats and are also riveted to the compression bar 2, and that the latter rivets extend through the flanges 38 of the bar 2 and through the flanges 41 of the journal box seats 39, and that additional rivets are provided for connecting the compression bar 2 to the journal box seat. It will also be observed that the intersection of the bars 8 with the compression bar 2 is closely adjacent the vertical planes passed through the center of the truck axle, and that while this inward spacing of the points of connection of the bars 8 and 2 from the vertical planes passing through the car axles will produce a cantilever action in the journal box seat members, the reaction point of the cantilever so formed, lies within the point of union of the compression and tension bars 2 and 8, respectively, and therefore this reaction will be taken by both the compression and tension bars.

It will also be observed that by providing journal box tie members of the form shown and described herein, and by connecting these tie members to the journal boxes in the manner shown, I greatly strengthen the side frame against lateral twisting, the said journal box tie members acting as a truss to prevent this twisting movement.

While I have described my construction in great detail, it should be noted that the words employed are to be taken in their descriptive and not their limiting sense, since what I claim and desire to secure by Letters Patent is:

1. A truck side frame, comprising channel shaped top and flanged bottom arch members and an interposed strut, and means for connecting said members adjacent the ends thereof, each of said means including a member and a plurality of rivets, some of

said rivets extending through the flanges of said arch members and connecting the same to the connecting member.

2. A truck side frame, comprising a flanged top and a plurality of bottom arch members having overlapping ends and means for connecting said members, said means involving a metallic member and a plurality of rivets, some of said rivets connecting a bottom arch member to the said metallic member, and some of said rivets connecting the said arch member to the flanges of said top arch member and to the said metallic member.

3. A truck side frame comprising a top arch member, a plurality of bottom arch members and a strut, said bottom arch members each comprising an angle bar and means for connecting the same to the strut and to the top arch member, said members having their end portions arranged in the same plane, the said end portions being adapted to lie adjacent the side edges of the top arch members.

4. A truck side frame comprising a top arch member, a plurality of bottom arch members and a strut, said bottom arch members each comprising an angle bar, said angle bars having their depending flanges spaced apart, and means for connecting the same to the strut and to the top arch member, the portions of said bottom arch members adjacent the top arch member being adapted to embrace the same.

5. A truck side frame comprising a top arch member, a plurality of bottom arch members and a strut, said bottom arch members each comprising an angle bar, said angle bars having their depending flanges spaced apart, the transversely extending flanges of the said bars being oppositely disposed, and means for connecting the said flanges to the strut, and means extending through the said flanges for connecting the same to the outer faces of the top arch member.

6. A truck side frame comprising a top arch member, a plurality of angle shaped bottom arch members and a strut, said bottom members at a point on opposite sides of the said strut each having one of the flanges thereof warped into the plane of the other flange thereof.

7. In a truck side frame, the combination of an upper arch member, a strut and a plurality of lower arch members, and means for connecting said members adjacent the ends thereof, said means including a pair of journal box seats, said lower arch members extending under the strut member and each having its end portions extending in a plane parallel to the coacting portion of the upper arch member.

8. In a truck side frame, the combination with a channel shaped upper arch member

and a strut, of a plurality of tension members adapted to connect the arch member and strut, and means for connecting the said members adjacent the ends thereof, said means including members seated in the channel of the upper arch member, portions of said tension members lying outside the planes defined by the flanges of the channel arch member.

10. 9. In a truck side frame, the combination with a flanged upper arch bar and a strut, of a plurality of flanged lower arch bars, and means interposed between flanges of the said upper arch bar said means being 15 adapted to engage the said lower arch bars adjacent the ends thereof, and rivets for connecting said bars to said means.

10. In a truck side frame, the combination with a channel shaped upper arch bar, 20 the flanges of which are downwardly directed, of a pair of spaced lower arch bars the ends of the last named bars overlying the adjacent flanges of the said top arch bar, and means for connecting the respective arch bars adjacent the ends thereof including members seated within the channel 25 of the upper arch bar.

11. In a truck side frame, the combination with a flanged upper arch bar, of a pair of 30 flanged lower arch bars and an interposed strut, the lower arch bars being adapted to be connected to the upper arch bar adjacent the ends thereof, portions of said lower arch bars intermediate the said strut and the said 35 points of connection with the said upper arch bar being warped and arranged in spaced planes parallel to the planes of the flanges of the said upper arch bar.

12. In a truck side frame, the combination with a flanged upper arch bar and a strut, of a pair of lower arch bars, each 40 adapted to underlie the said strut and each extending upwardly and outwardly therefrom, and means for connecting the lower arch bars to the upper arch bar adjacent the ends of the latter, the end portions of the said lower arch bars extending outside of and parallel to the flanges at the end portions of the said upper arch bar.

13. In a truck side frame, the combination with an upper arch member and a lower arch member, said lower arch member being composed of a plurality of angle bars, of a 45 strut interposed between said upper and lower members, said strut comprising a hollow box member having portions adapted to enclose neighboring portions of the angle bars comprising the lower arch member, and means connecting the strut to said arch member.

14. In a truck side frame, the combination with a flanged upper arch member, and flanged lower arch members, of an interposed strut, said strut comprising a pair of 55 side members, a top member and a bottom

member provided with spaced flanges, and means for connecting the said top member to the upper arch member, the lower arch members extending between and respectively connected to the said flanges of the 70 strut bottom member.

15. In a truck side frame, the combination with a channel shaped upper arch bar and a hollow box shaped strut, of a pair of warped flanged lower arch or tension members and a pair of flanged journal box tie bars, and means for uniting said members.

16. In a truck side frame, the combination with a channel shaped upper arch or compression member, and a hollow box strut, of a pair of flanged tension members each having one of the flanges thereof warped into the plane of the other flange adjacent the ends of the said member, the said strut overlying and being connected to both of the said flanges of each of the said tension members, and a portion of the said strut extending within and being connected to the said channel arch member.

17. In a truck side frame, the combination with a channel shaped upper arch bar having the flanges thereof downwardly directed, of a pair of angle bar lower arch members, a strut interposed between said arch members, said angle bar members being substantially uniform in section from end to end, and means for connecting said arch members adjacent the end portions thereof.

18. In a truck side frame, the combination with a channel bar compression member having downwardly directed tapering flanges, of an integral box shaped strut and a pair of cast journal box seats, portions of the strut and the said cast seats being shaped to fit within said channel bar and being 100 spaced from the inner face of the web thereof.

19. In a truck side frame, the combination with upper and lower arch bars of an interposed strut, said strut including a pair of 110 spaced upright columns, each of which is provided with a countersunk seat, bolster guide plates removably mounted on said seats, and means comprising a U-shaped member, the end portions of which extend 115 through suitable openings in the guide block and the adjacent column for removably securing each block in position.

20. In a truck side frame, the combination with upper and lower arch bars, and an interposed strut, of a plurality of pairs of journal box tie members, each of said pairs comprising two counterpart flanged bars, one end of each bar being connected to the 120 said strut, the opposite ends of the said bars being adapted to overlap beneath the adjacent journal box and each having alined perforations to receive the journal box bolts.

21. A journal box tie member for arch bar trucks comprising a pair of counterpart 125

members each of which is provided with a tapering upright flange and is formed from sheared plate.

22. A journal box tie member for arch bar trucks comprising a pair of plates each of which is substantially uniform in section and each of which is provided with a pair of oppositely tapered flanges.

23. A journal box tie member for arch bar

trucks comprising a pair of flanged plates 10 the inner ends of which are spaced apart and connected to a strut member and the outer ends of which overlap, said overlapping ends underlying the adjacent journal box and being connected thereto. 15

In testimony whereof I affix my signature.

DONALD S. BARROWS.
